UNITED STATES PATENT OFFICE.

WILLIAM ARTHUR RAMSAY, OF HONOLULU, TERRITORY OF HAWAII.

MEANS FOR CONVEYING MACERATED BAGASSE BETWEEN SUGAR-MILLS.

1,204,314.

Specification of Letters Patent.

Patented Nov. 7, 1916.

Application filed February 25, 1915. Serial No. 10,623.

To all whom it may concern:

Be it known that I, WILLIAM ARTHUR RAMSAY, a subject of the King of Great Britain, residing at Honolulu, in the Territory of Hawaii, have invented certain new and useful Improvements in Means for Conveying Macerated Bagasse Between Sugar-Mills, of which the following is a specification.

10 In my co-pending application, Serial No. 830,000 there is disclosed an apparatus for macerating sugar cane which includes as a collateral, though important, feature an improved means or agency for transferring the macerated bagasse from one sugar mill to the mill next in order in the series.

20 The present invention relates broadly to an apparatus for macerating sugar cane of the general type shown in my said co-pending application and, specifically, to an improvement in the means for transferring the macerated bagasse from one mill to another.

25 The objects of the invention, briefly stated, are to provide a bagasse transferring means of such nature that the transfer of the bagasse is due, in part, to the ejecting power of the mill from which the bagasse is discharged and, in part, to a positively acting 30 mechanical agency; to provide a bagasse transferring means of unitary nature and structurally independent of the mills which it connects whereby said means may be removed or replaced as a unit relatively to said 35 mills and without entailing any dismantling of the mills; to provide a bagasse transferring means having the characteristics stated, which is so related to the mills which it connects that the rolls of said mills may be removed, in the customary manner, without 40 the necessity of dismantling or in any way disturbing the bagasse transferring means; to provide a bagasse transferring means, which notwithstanding its capacity for unitary removal and replacement, shall when 45 in its operative position, have smooth, close and tight jointure with the parts against which it is fitted; to provide a bagasse transferring means which shall be readily accessible for cleaning or other purposes; and to provide a bagasse transferring means which is particularly facile and reliable in its operation.

50 With the above and other objects and advantages in view, which will be pointed out as the description proceeds, the improved

bagasse transferring means consists generally of a chute formed to utilize the ejecting power of the discharge mill, preferably as in my co-pending application, and a conveyer working in the upper portion of the chute and mechanically and positively aiding the passage of the bagasse from one mill to the other.

55 An embodiment of the invention is illustrated in the accompanying drawings, wherein:

Figure 1 is a side elevation showing the bagasse transferring means in its operative relation between a pair of adjoining mills. 79 Fig. 2 is a top plan view thereof. Fig. 3 is a longitudinal sectional view thereof. Fig. 4 is a detail sectional view on the line 4-4 of Fig. 1. Fig. 5 is a diagram showing the bagasse transferring means as removed from between the mills which it normally connects and showing (by dotted lines) the conveyer as elevated from its normal horizontal position.

80 Similar characters of reference designate corresponding parts throughout the several views.

85 The invention is not concerned with the construction of the mills and of the macerating scraper and these elements, therefore, need no detail description, it being sufficient to point out that the mills are shown at A and B, A being the discharge mill and B the receiving mill and the macerating scraper (which is preferably of the construction shown in my said co-pending application) at C, said scraper being arranged at the discharge side of the mill A.

90 The essential element of the bagasse transferring means, is a chute designated generally by the numeral 1 and comprising a bottom 2 and vertical side walls 3. The side walls are preferably provided adjacent their lower edges with longitudinal angle irons 4 conforming to the desired outline of the bottom 2 and supporting the same. The bottom 2, in the embodiment shown, is of curved form in longitudinal outline, being directed upwardly at an appropriate angle from the mill A for approximately a third 100 of its length and being directed downwardly toward the mill B for the remainder of its length, the upwardly and downwardly directed portions being united along a gradual curve.

105 When the usual three roll mills are employed, the bagasse is ejected from one mill

- at an upward angle of inclination and is delivered into a succeeding mill at a downward angle of inclination. By making the bottom 2 of the form described, the chute is adapted to existing standards of construction and operation and the further advantage is secured of utilizing the ejecting power of the mill A for the transfer of the bagasse.
- 5 The chute is supported at one end by being fitted against the side plates of the macerating scraper 6 and at its other end by means of brackets 6 secured to the housing of the mill B. The brackets 6 in addition to their function of supporting the chute also form extensions of the side walls thereof and hence are co-planar with said side walls. Said brackets 6 are connected at their lower edges by a plate 8 which forms 10 a continuation of the bottom 2. To enable the brackets 6 and the side plates of the macerating scraper to exercise their supporting functions, the mating edges of said brackets and of the adjacent side walls 3 and side plates of the scraper are formed along downwardly converging inclines, as at 9, whereby the chute has a downward wedge fit, so to speak, between the side plates of the scraper and the brackets 6.
- 15 It is preferred to provide lap joints between the walls 3 and the bottom 2 and the chute extension, formed by the brackets 6 and the plate 8. The lap joint between the bottom 2 and the plate 8 is provided by extending the bottom for a short distance beyond the side walls 3 whereby said bottom overlaps the plate 8 as shown in Figs. 3 and 4. The lap joints between the side walls 3 and the brackets 6 are provided by securing reinforcing plates 10 to the outer faces of said 20 brackets and which project slightly beyond said brackets and by securing strips 11 to the side walls 3 in such relation that, in combination with said side walls, said strips 25 define grooves or recesses (Fig. 4) in which the projecting portions of the plate 10 have relatively close fit.
- 25 The chute is employed in combination with a conveyer which, in its preferred embodiment, consists of longitudinally arranged endless chains 12 connected at appropriate intervals by transverse slats 13. The chains 12 are trained over sprockets 14 and 15, the sprocket 14, arranged adjacent the mill A, being mounted upon a transverse drive shaft 16 and the sprockets 15, arranged adjacent the mill B and serving as idlers, being mounted upon a transverse shaft 17 which has no fixed bearings and 30 hence may be termed a "floating" shaft.
- 35 The shaft 16 is journaled in bearings 18, one of which is mounted upon a side wall 3 and the other of which is mounted upon a bracket 19 located beyond the other side wall 3 and secured to the mill housing. The 35 bearings 18 are preferably open in order that the shaft 16 may be readily lifted from position when the occasion may require. The shaft 16 beyond the bracket 19 carries a driving sprocket 20 which is loose on said shaft and has its hub provided with ratchet clutch teeth 21 which engage with similar teeth formed at the adjoining end of a clutch sleeve 22. The sleeve 22 is splined on the shaft 13 and is urged against the sprocket 20 by a spring 23 arranged on the shaft 16 between the outer end of said sleeve and a thrust collar 24.
- 40 The shafts 16 and 17 are connected by radius rods 25 through the intermediary of T couplings 26 and retaining collars engaging against said couplings. The conveyer as an entirety is thus supported from the shaft 16 as a fulcrum and the slats 13 bear with constant pressure on the bagasse passing along the chute. By virtue of the pressure which the conveyer slats thus exert on the bagasse, the action of the conveyer in feeding or assisting in feeding the bagasse along the chute is rendered certain and reliable. At the same time, inasmuch as the feeding of the bagasse is due, in large part, to the ejecting power of the mill A and the greater part of the travel of the bagasse is along a downward incline toward the mill 45 B, the conveyer requires comparatively little power for its efficient operation. Since the shaft 17 is a "floating" shaft and is connected to the shaft 16 by the radius rods 25, it follows, that the conveyer automatically 50 adjusts itself, (i. e. rises and falls) to variations in the thickness of the stream of bagasse.
- 55 Access to the chute may be had, if desired, without the necessity of removing the chute from between the mills, or without removing the conveyer from the chute, simply by lifting the conveyer into a vertical or other suitable position about the shaft 16 as a pivotal axis. In such movement of the 50 conveyer, the teeth of the clutch sleeve 22 will ride over the teeth 21 as is obvious.
- 60 The chute is reinforced by the angle irons 4, previously mentioned, by other longitudinal angle irons 27 extending along the upper edges of the walls 3, by transverse angle irons 28 arranged at appropriate intervals under the bottom 4 and by distance bolts and sleeves 29 connecting the walls 3 at the upper corners thereof. The 65 angle irons 27 are provided at their ends with apertures 30, the purpose of which is to receive the hooks 31 of a suitable implement 32 employed to lift the chute from between the mills A and B whenever the occasion may require.
- 70 When the chute is to be removed from between the mills or the conveyer is to be removed from the chute without moving the latter from between the mills, the chain 75

which drives the sprocket 20 is disengaged from said sprocket in any usual manner. Thereupon, the chute and conveyer as a unit may be removed from position between the mills or the conveyer may be removed from the chute proper without disturbing the position of the latter. The arrangement of the chute between the mills and the manner in which the chute is supported is such that the front and back rolls of the mills may be removed in the usual manner and for the usual purposes without disturbing the chute. The macerating scraper C, as stated, is preferably of the construction shown in my said co-pending application and in any event, is formed with a bagasse passage of which the chute forms a continuation.

Having fully described my invention, I claim:

1. The combination of a chute to extend between successive sugar mills and along which the bagasse is fed and a macerating scraper adjacent the inlet end of the chute, the chute being removable from between the scraper and the next succeeding mill by a lifting movement.

2. The combination of a chute to extend between successive sugar mills and along which the bagasse is fed, a macerating scraper adjacent the inlet end of the chute provided with side plates, and brackets adjacent the discharge end of the chute, said plates and brackets engaging the side walls of the chute to support the latter and being formed to permit of the removal of the chute by a lifting movement thereof.

3. The combination of chute to extend between successive sugar mills and along which the bagasse is fed, a macerating scraper adjacent the inlet end of the chute provided with side plates, and brackets adjacent the discharge end of the chute, said plates and brackets engaging the side walls of the chute to support the latter, the meeting edges of the side walls of the chute and of said plates and brackets, respectively, being formed along converging lines of inclination whereby the chute may be removed from position by a lifting movement.

4. The combination of a chute to extend between successive sugar mills and along which the bagasse is fed, a macerating scraper adjacent the inlet end of the chute provided with side plates, and brackets adjacent the discharge end of the chute, said plates and brackets engaging the side walls of the chute to support the latter and being formed to permit of the removal of the chute by a lifting movement thereof, the brackets being co-planar with the side walls of the chute and forming continuations thereof and being connected by a transverse plate which forms a continuation of the bottom of the chute.

5. The combination of a chute to extend

between successive sugar mills and along which the bagasse is fed, a macerating scraper adjacent the inlet end of the chute provided with side plates, and brackets adjacent the discharge end of the chute, said plates and brackets engaging the side walls of the chute to support the latter and being formed to permit of the removal of the chute by a lifting movement thereof, the brackets being co-planar with the side walls of the chute and forming continuations thereof and being connected by a transverse plate which forms a continuation of the bottom of the chute, the meeting edges of the side walls of the chute and of said brackets and of the bottom of the chute and said transverse plate being formed to provide lap joints.

6. The combination of a chute to extend between successive sugar mills and along which the bagasse is fed and a conveyer operating above said bottom in spaced relation thereto and upon the upper side of the stream of bagasse.

7. The combination of a chute to extend between successive sugar mills and having side walls and a bottom along which the bagasse is fed and an endless conveyer working longitudinally within the chute wholly above said bottom, the lower run of said conveyer operating in spaced relation to said bottom and upon the upper side of the stream of bagasse.

8. The combination of a chute to extend between successive sugar mills and along which the bagasse is fed, the chute having side walls and a bottom and an endless conveyer working longitudinally within the chute above the bottom thereof, the conveyer including endless conveyer means, driving gears therefor, idlers therefor, a driving shaft carrying driving gear, a floating shaft carrying the idlers, and radius rods connecting said shafts.

9. The combination of a chute to extend between successive sugar mills and along which the bagasse is fed, the chute having side walls and a bottom and an endless conveyer working longitudinally within the chute above the bottom thereof, the conveyer including endless chains, driving sprockets therefor, idler sprockets therefor, slats connecting said chains, a driving shaft carrying said driving sprockets, a floating shaft carrying said idler sprockets and radius rods connecting said shafts.

10. The combination of a chute to extend between successive sugar mills and along which the bagasse is fed, the chute having side walls and a bottom, and a conveyer working longitudinally of the chute above the bottom thereof and having a relatively fixed transverse pivotal axis at one end and its other end free.

11. The combination of a chute to extend

between successive sugar mills and along which the bagasse is fed, the chute having side walls and a bottom, and an endless conveyer working longitudinally of the chute 5 above the bottom thereof and having a relatively fixed transverse pivotal axis at one end and its other end free.

12. The combination of a chute to extend between successive sugar mills and along 10 which the bagasse is fed, the chute having side walls and a bottom, and an endless conveyer working longitudinally of the chute above the bottom thereof and having a relatively fixed transverse pivotal axis at one 15 end and its other end free, and a transverse driving shaft for said conveyer and constituting said pivotal axis thereof.

13. The combination of a chute to extend between successive sugar mills and along 20 which the bagasse is fed, the chute having side walls and a bottom, and an endless conveyer working longitudinally of the chute above the bottom thereof and having a rela-

tively fixed transverse pivotal axis at one end and its other end free, a transverse driving shaft for said conveyer and constituting said pivotal axis, and open bearings for 25 said shaft.

14. The combination of a chute to be supported between successive sugar mills and along which the bagasse is fed, the chute being removable from between the mills by a lifting movement, and a conveyer working longitudinally within said chute and removable therewith from between the mills, the 30 conveyer being independently removable from said chute by a lifting movement apart from the lifting movement necessary to remove said chute from between the mills.

In testimony whereof I have hereunto set 35 my hand in presence of two subscribing witnesses.

WILLIAM ARTHUR RAMSAY.
